UNITED STATES PATENT OFFICE.

CHARLES P. PRICE, OF BOSTON, MASSACHUSETTS.

DESIGN FOR A VENDING-MACHINE CASING.

Application filed July 25, 1925. Serial No. 14,224. Term of patent 14 years.

To all whom it may concern:

Be it known that I, CHARLES P. PRICE, a citizen of the United States, residing at Boston, in the county of Suffolk, State of Massachusetts, have invented a certain new, original, and ornamental Design for Vending-Machine Casings, of which the following is a specification, reference being had to the accompanying drawing, forming part thereof.

The figure is a perspective view of a vending machine casing, showing my design.

I claim:

The ornamental design for a vending machine casing, substantially as shown.

In testimony whereof, I affix my signature.

CHARLES P. PRICE.
